DESIGN FOR A CURTAIN

Samuel Libou, New York, N. Y., assignor to Eastern Trimming & Cord Co., Inc., New York, N. Y., a corporation of New York

Application March 6, 1935, Serial No. 55,755

Term of patent 3½ years

To all whom it may concern:

Be it known that I, Samuel Libou, a citizen of the United States of America, residing at New York, in the county of New York and State of New York, have invented a new, original, and

ornamental Design for a Curtain, of which the following is a specification, reference being had to the accompanying drawing, forming a part hereof.

The single figure of the drawing is a view showing substantially one-half of the curtain, the broken away portion intermediate the top and bottom being a repeat of the design shown in the body of the curtain and indicated at A.

I claim:

The ornamental design for a curtain as shown and described.

SAMUEL LIBOU.
